DESIGN FOR AN ELECTRICAL APPLIANCE CABINET

William J. Conwell, Elwood, Ind., assignor to G. I.
Sellers & Sons Company, Elwood, Ind., a corpo-
ration of Indiana

Application October 16, 1940, Serial No. 95,877

Term of patent 3½ years

To all whom it may concern:

Be it known that I, William J. Conwell, a citizen of the United States, residing at Elwood, in the county of Madison and State of Indiana, have invented a new, original, and ornamental Design for an Electrical Appliance Cabinet, of which the following is a specification, reference being had to the accompanying drawing, forming part thereof.

Figure 1 is a front perspective view of an electrical appliance cabinet showing my new design.

Figure 2 is a perspective view showing a table top member in its extended position.

Figure 3 is a front perspective view with certain elements in open position.

The rear of the cabinet and the side opposite that shown in the drawing are substantially plain.

The characteristic features of my design reside in the portions shown in solid lines.

I claim:

The ornamental design for an electrical appliance cabinet, substantially as shown and described.

WILLIAM J. CONWELL.
